UNITED STATES PATENT OFFICE.

SUMNER A. GILMAN, OF BOSTON, MASSACHUSETTS.

DESIGN FOR A ROOF-FENDER.

SPECIFICATION forming part of Design No. 27,515, dated August 10, 1897.

Application filed July 3, 1897. Serial No. 643,459. Term of patent 14 years.

To all whom it may concern:

Be it known that I, SUMNER A. GILMAN, a citizen of the United States, residing at Boston, in the county of Suffolk and State of Massachusetts, have invented and produced a new and original Design for Roof-Fenders, of which the following is a specification, reference being had to the accompanying drawing, forming a part thereof.

10 The drawing shows in perspective a roof-fender embodying this invention.

As shown in the drawing, the leading or material feature of my design consists of a number of narrow parallel bars, which form 15 the brace of the bracket of the fender, and a number of parallel bars, which form the table of the bracket of the fender, they being so disposed as to present the appearance of a number of connected brackets.

20 *a* represents a rectangular wall-plate hav-

ing triangular holes *b* and projections *c* of a corresponding shape.

d d represent narrow parallel bars, which form the brace of the bracket of the fender, and *e e* represent similar narrow parallel bars, 25 which form the table of the fender.

f is a square opening in the wall-plate just above the table.

The triangular holes *b* and projections *c* may be omitted.

I claim—

The design for roof-fender, substantially as herein shown and described.

In testimony whereof I have signed my name to this specification in the presence of 35 two subscribing witnesses.

SUMNER A. GILMAN.

Witnesses:

B. J. NOYES,

ARTHUR F. RANDALL.
